UNITED STATES PATENT OFFICE

ADOLPH J. BISEK, OF LOWRY, MINNESOTA

END-GATE LOCK

Application filed November 17, 1926. Serial No. 143,840.

My invention relates to end-gates for farm wagons wherein it is designed to provide a gate which may be used in a manner so that it can be readily collapsed or released when it is desired.

A feature of the invention resides in an end-gate which will lock securely in place without danger of having the same become disengaged accidentally, yet having a simple and practical construction which may be easily made up and readily operated.

My invention includes an end-gate which is provided with a hinged portion having a projecting board which is adapted to carry the released lever of the gate catch on the free end of the same. The back board of the gate is adapted to carry the locking lug and it is a feature of the invention to provide a locking lug which is adjustable so that the catch may be adjusted to operate properly when the parts are connected together.

My end-gate is adapted to be readily operated and a feature of the invention resides in a catch having a plate member within which is positioned a rotatable locking cam which is slotted to engage over the locking bolt and is held rotatable so as to rotate into a position to engage against threaded portions formed on the bolt to lock the portions of the end-gate firmly together and against rattling. I provide a spring catch in the lever which is adapted to positively lock the operating lever in position to hold the catch locked closed. By simply pressing this lever inward the locking lug is released and the catch may be disengaged so as to permit the end-gate to fold in a manner to be readily removed.

These features, together with other details and objects of the invention will be more fully and clearly set forth in the specification and claims.

In the drawings forming part of this specification:

45 Figure 1 illustrates my end-gate in side elevation.

Figure 2 is a section on the line 2—2 of

Figure 1.

Figure 3 is a cross section on the line 3—3 of Figure 1.

Figure 4 is taken on the line 4—4 of Figure 3, showing the back of the catch with the under plate removed to expose the cam plate which is rotated by the lever under the top plate.

55 In the drawings my end-gate is formed with a back portion 10 to which is hingedly secured the short end portion 11 on one side by means of hinges 12.

The short end portion is adapted to carry the releasing member 13 which is secured by the rivet members 14 to the short end board 11 of the end-gate A. The free end of the member 13 is adapted to carry the operating catch B for my end-gate A.

60 The back board 10 of the end-gate A together with the short end 11 are adapted to extend in line or approximately the same plane and the back board 10 is adapted to support the bolt 15 of the catch B. The bolt 15 is threaded at 16 into the shank 17 of the plate 18. The plate 18 is adapted to be held by the bolts 19 rigidly secured and attached to the back board 10. I provide a locking nut 20 which permits the bolt 15 to be locked 65 adjusted to the back board 10 and in this manner the bolt 15 can be lengthened or shortened so as to properly position the outer threaded end 21 of the same so that it will properly engage in operation with the catch 70

75 B. The catch B is provided with an outer plate member 24 which is held by corner screws 25 so as to attach the plate 24 firmly to the free end of the locking board or member 13. The plate 24 is formed with a central 80 arcuated portion 26 which is adapted to fit over the head 27 of the bolt 15, while I provide an annular groove 28 about the center portion 26 which is adapted to receive the annular bead 29 formed on the cam locking plate 85

30. The plate 30 is of a flat nature having the annular bead 29 projecting about the same which fits in the groove 28 and having cam projecting shoulders 31 formed integral therewith which is adapted to project in a 90 manner so as to engage with the threads 21 of the bolt 15 when the plate 30 is rotated.

95 The plate 30 is formed with an operating tongue end 32 which projects from one side of the same and to which an operating lever 33 100

is pivotally attached at 34. The operating lever 33 is formed of sheet metal or similar material to have a hollow nature permitting a tongue 32 to extend within the same so that the tongue 32 may operate within the handle 33 of the lever. A flat spring 35 is interposed between the free end of the tongue 32 and the inner surface of the lever 33, being held in position by the pin 36 which is riveted to the inner end of the lever 33 and the end 37 of which is adapted to extend through the hole 38 in the outer plate 24, when the lever 33 is in the downward position as illustrated in dotted outline in Figure 1. The lever 33 is illustrated in full lines in the released position with the end 37 of the pin 36 bearing on the outer surface of the plate 24 when the lever 33 is in released position and rotated away from the opening 38. The plate 30 is formed with an opening 39 which permits the end 37 of the pin to extend through the hole 38 in the plate 24 and into the opening 39 in the plate 30. This holds the lever 33 in locked position with the locking cam shoulders 31 engaging against the threads on the bolt 15. The bolt 15 is formed with flat sides 15' and the opening 40 through the plate 30 is of an elongated nature with the cam shoulders 31 projecting on either side of the same. The outer plate 24 of my catch B is formed with an arcuated slot 42 through which the tongue 32 projects to permit the rotation of the plate 30 in operation. In operation, when the catch B is desired to be released the free end of the lever 33 is pressed against the spring 35 lifting the end 37 of the pin 36 out of the openings 39 and 38 permitting the lever 33 to be rotated which rotates the plate 30 to disengage the cam shoulders 31 from the threads 21 of the bolt pin 15 and cause the elongated hole 40 to line up with the elongated shape of the flat sides 15' of the pin 15, thereby permitting the free end of the member 13 to be released from the pin 15 and moved away from the back board 10. Thus the end-gate A is released by folding with the hinges 12 so that the short end 11 may fold toward the back board 10 and the length of the end-gate is thereby shortened, permitting the end-gate to be released from the wagon. In this manner I provide an end-gate which is securely locked when the lever 33 is in position to snap the pin 37 into the openings 38 and 39 and to positively prevent the end-gate from becoming loose unless it is released by pressing the lever 33 inward. I have thoroughly tested my end-gate in actual use and have found it to be very practical, overcoming the objectionable feature of ordinary end-gates which are so easily disengaged from the vibration of the wagon or truck and thus by using my form of end-gate the same will not become accidentally disengaged and be lost. This is an important in-

vention in this detail as many times end-gates coming loose cause the loss of grain to the farmer which is an expensive and aggravating occurrence.

In accordance with the patent statutes I have described the principles of operation together with illustrations to indicate the best embodiment thereof, but I desire to have it understood that the drawings are only suggestive of a means of carrying out my invention and a particular way of making my end-gate and catch and that the invention may be applied to other uses and carried out by other means within the scope of the following claims without departing from the spirit of my invention.

I claim:

1. A catch for an end-gate including, an adjustable bolt secured to one portion, a rotatable plate having cam engagement with said bolt, and a lever adapted to release said rotatable plate or to operate the same into locking position.

2. A catch for an end-gate including, a plate member, a rotatable cam member positioned on said plate member, an outer plate member adapted to hold said rotatable cam member in operative position, a tongue projecting from said cam member, an operating lever pivoted to said tongue, a pin on one end of said lever, and a recess for receiving said pin to hold said plate in locking position on a bolt projecting from the back of the end-gate.

3. A catch for an end-gate including, an adjustable bolt having a plate-like back portion, means for locking said bolt in adjusted position, a threaded end formed on said bolt, flat side portions on said bolt, a cam locking plate having an elongated opening adapted to fit over said flat side portions of said bolt in one position, and cam shoulders formed on said plate adjacent said opening adapted to engage said threaded end to lock an end-gate.

4. An end-gate lock including, a rotatable cam plate member, a bearing plate for said plate member, a guide plate adapted to extend over said plate member, an adjustable bolt having a threaded cam end adapted to permit said cam plate to engage the same when it is rotated to lock the parts of the end-gate together.

5. A catch member having inner and outer plate members, a rotatable cam plate member interposed between said plate members, a locking bolt adapted to be secured to one of the members of said end-gate, a tongue projecting from said rotatable cam member, and a spring operated handle pivotally secured to said tongue in a manner so as to be depressed to release said plate from locking position.

ADOLPH J. BISEK.
